Primary Examiner — Ian Simmons*Assistant Examiner* — Charles Hanson(74) Attorney, Agent, or Firm — Ryan N. Carter(57) CLAIM

The ornamental design for a cosmetic clutch carrying case, as shown and described.

DESCRIPTION

FIG. 1 is a perspective view of the device in its closed position;

FIG. 2 is a side view of the device in its closed position;

FIG. 3 is an end view of the device in its closed position;

FIG. 4 is a top view of the device in its closed position;

FIG. 5 is a bottom view of the device in its closed position;

FIG. 6 is a perspective view of the device in its open position;

FIG. 7 is a top view of the device in its open position with the mirror in a first position; and,

FIG. 8 is a top view of the device in its open position with the mirror in a second position.

The broken line showing of the items in the case is included for the purpose of illustrating environment and forms no part of the claimed design.
